US00D831604S

(12) **United States Design Patent** (10) **Patent No.:** **US D831,604 S**
(45) **Date of Patent:** ** *Oct. 23, 2018

(54) **MOBILE PHONE**

(71) Applicant: **LG ELECTRONICS INC.**, Seoul (KR)

(72) Inventors: **Hyunggon Ryu**, Seoul (KR); **Minsun Park**, Seoul (KR); **Woonlee Park**, Seoul (KR); **Kyubong Choi**, Seoul (KR)

(73) Assignee: **LG ELECTRONICS INC.**, Seoul (KR)

(*) Notice: This patent is subject to a terminal disclaimer.

(**) Term: **15 Years**

(21) Appl. No.: **29/588,778**

(22) Filed: **Dec. 22, 2016**

(30) **Foreign Application Priority Data**

Jun. 24, 2016 (KR) 30-2016-0031038

(51) **LOC (11) Cl.** **14-03**

(52) **U.S. Cl.** ..... **USPC ..... D14/138 G**

CLAIM

The ornamental design for a mobile phone, as shown and described.

DESCRIPTION

FIG. 1 is a front perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The broken lines depict portions of the mobile phone that form no part of the claimed design.

1 Claim, 7 Drawing Sheets
